UNITED STATES PATENT OFFICE.

EDMUND E. PECK, OF BROOKLYN, NEW YORK.

DESIGN FOR A STUDENT-CHAIR.

SPECIFICATION forming part of Design No. 23,066, dated February 13, 1894.

Application filed January 5, 1894. Serial No. 495,869. Term of patent 3½ years.

To all whom it may concern:

Be it known that I, EDMUND E. PECK, a citizen of the United States, residing at Brooklyn, in the county of Kings, State of New York, 5 have invented and produced a new and original Design for Student-Chairs, of which the following is a specification, reference being had to the accompanying drawing, showing a part thereof, in which the figure is a view of 10 a chair embodying my design.

The leading feature of my design consists primarily in the shape of the chair. This particular style of chair is that well known as student-chairs. In this class of chairs the 15 space between the arm and seat is ordinarily closed while the seat is horizontal.

In the drawing, A represents the seat frame, the side-bars of which sweep downward. The rear legs, B, are approximately S- 20 shaped and sweep upward above the seat frame ending in a knob or scroll ornamentation, b. The back frame, C, is inclined at an angle of about forty-five degrees and is se-

cured to the rear legs, B, above the seat-frame. The forward legs, D, support the forward edge of the seat frame and are formed on foot-curve lines. The arms, H, extend from the back frame, C, and sweep vertically upward in the plane of the side-bars of the seat frame, A. Said arms are supported ; by ornamental posts, h, at their forward ends, said posts being mounted on the side-bars of the seat frame. The space, x, is thus left under the arm. The upholstering, K, is tufted and a fringe, m, is pendent from the arms. 35

The back-frame, A, has its upper ends extended or curved outwardly at, p.

Having thus explained my design, what I claim is—

The design for a student-chair substantially as herein shown and described. 40

EDMUND E. PECK.
